Fig-6

FIGURE 1 is a perspective view of a child's stroller or similar article showing my new design with one end of the seat belt in the unattached position;

FIGURE 2 is a front elevational view;

FIGURE 3 is a rear elevational view;

FIGURE 4 is a side elevational view;

FIGURE 5 is a plan view; and

FIGURE 6 is a bottom underside view thereof.

It is understood that the cross-hatching shown indicating material change is continuous throughout the areas indicated.

I claim:

The ornamental design for a child's stroller or similar article, as shown and described.
